UNITED STATES PATENT OFFICE

163,272

DEFLECTOR FOR AUTOMOBILE
WINDSHIELDS

Max Glass, Chicago, Ill.

Application July 14, 1950, Serial No. 11,190

Term of patent 14 years

(Cl. D14—6)

To all whom it may concern:

Be it known that I, Max Glass, a citizen of the United States, residing at 914 Diversey Parkway, Chicago, Illinois, have invented a new, original, and ornamental Design for a Deflector for Automobile Windshields, of which the following is a specification, reference being had to the accompanying drawing, forming a part thereof.

Figure 1 is a front view of a deflector for automobile windshields showing also, in dotted lines, one type of mounting bracket;

Figure 2 is a top view of the deflector of Figure 1; and

Figure 3 is a side view thereof omitting the mounting bracket of Figure 1.

The dotted lines of Figure 1 show one conventional type of mounting bracket for the deflector of the present design, which mounting bracket is shown for illustrative purposes only.

I claim:

The ornamental design for a deflector for automobile windshields, substantially as shown and described.

MAX GLASS.
